[57] CLAIM

The ornamental design for the computer workstation with telephone for the corporate beginner, as shown and described.

DESCRIPTION

FIG. 1 is a front elevational view of the computer workstation with telephone for the corporate beginner showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an enlarged perspective view thereof.

The broken lines are shown for illustrative purposes only and form no part of the claimed design.
